UNITED STATES PATENT OFFICE.

SAMUEL G. MILLIGAN, OF HARWICK, PENNSYLVANIA.

VALVE DEVICE FOR INTERNAL-COMBUSTION ENGINES.

1,260,933.

Specification of Letters Patent. Patented Mar. 26, 1918.

Application filed June 22, 1916. Serial No. 105,122.

To all whom it may concern:

Be it known that I, SAMUEL G. MILLIGAN, a citizen of the United States, residing at Harwick, in the county of Allegheny and State of Pennsylvania, have invented 5 certain new and useful Improvements in Valve Devices for Internal-Combustion Engines, of which the following is a specification.

10 This invention relates to improvements in valve devices for internal combustion engines, and particularly to an engine of the four cycle multi-cylinder type.

15 The primary objects of this invention are to provide valve devices of the character specified, wherein rotating valves, with large bearing surfaces and operated directly from the crank shaft are utilized for controlling both the inlet and the exhaust, which are 20 noiseless and positive in their action and operation, and which are so constructed and operated as to prevent carbonization, thereby eliminating the necessity of grinding same.

25 Further objects of this invention are to provide valve devices of the rotary type, wherein the valves are mounted upon and operated by a single shaft, and in which the leakage of the gas mixture shall be effectively prevented or reduced to a minimum.

30 Still further objects of this invention are to provide a device for the purpose set forth, which is simple in its construction and arrangement, strong, durable and efficient in 35 its use, and inexpensive to manufacture.

To the accomplishment of these and such other objects as may hereinafter appear, the invention consists of the novel construction, combination and arrangement of parts specifically described, and illustrated in the accompanying drawing, wherein is shown an embodiment of the invention.

40 In the drawing, forming a portion of this specification, and wherein like numerals of reference designate corresponding parts throughout the several views:

45 Figure 1 is a longitudinal sectional view of the valve devices in accordance with this

invention, as applied to an internal combustion engine. 50

Fig. 2 is a cross sectional view on line $x-x$, in Fig. 1.

Fig. 3 is a detail plan view of the disk valve.

Fig. 4 is a cross sectional view on the line $y-y$, in Fig. 3.

Referring more in detail to the drawing, the numerals 1, 2, 3 and 4 designate the respective cylinders of the engine, here four in number, which are preferably made in 60 one casting.

Extending along the one side of the head portion of the engine is the valve casing 5, which is divided into as many separate valve chambers as there are cylinders and it is 65 therefore shown here as provided with four valve chambers 6, 7, 8 and 9, arranged to make communication, through the ports 10, 11, 12 and 13, with the cylinders 1, 2, 3 and 4 respectively. Portions of the valve chambers 6, 7, 8 and 9 are divided into upper sections 14, 15, 16 and 17, and into lower sections 18, 19, 20 and 21 by the centrally disposed walls 22, 23, 24 and 25, which extend from the ends 26, 27, 28 and 29 of the 75 valve chambers 6, 7, 8 and 9 to the valve seats 30, 31, 32 and 33.

The supply conduits communicate with said lower sections 18, 19, 20 and 21 through the ports 65, and the products of combustion 80 are exhausted through the ports 66, which are in communication with the upper sections 14, 15, 16 and 17.

The valve seats 30, 31, 32 and 33, one in each of the valve chambers 6, 7, 8 and 9 and 85 formed integral with the valve casing 5 or secured therein in any suitable manner, are provided with the inlet ports 34, 35, 36 and 37, which communicate with the lower sections 18, 19, 20 and 21 of the said valve 90 chambers; said valve seats are further provided with the exhaust ports 38, 39, 40 and 41 communicating with the upper sections 14, 15, 16 and 17 of the said valve chambers.

95 The inlet ports 34, 35, 36 and 37, and the exhaust ports 38, 39, 40 and 41 of the valve

seats 30, 31, 32 and 33, extend to the peripheries of said valve seats, and at said peripheries are commensurate to one-eighth the circumference of said disk valves. Portions 42, 5 as shown in Fig. 2, of the said valve seats, having the same peripherical measurements as one of the said inlet or exhaust ports, are disposed intermediate the said inlet ports and the said exhaust ports.

10 The shaft 43, provided with the driving gear 44 and suitably journaled at 45 and 46, extends longitudinally through the valve casing 5 and carries the disk valves 47. Said disk valves are provided with the hubs 48 15 and can be adjusted upon the said shaft by means of the set screws 49. The disk valves 47 are further provided with the ports 50, which are identical in contour to, and which are adapted to register with the inlet and 20 exhaust ports of the valve seats 30, 31, 32 and 33.

On the peripheries of the disk valves 47, are the flanges 51, disposed at right angles thereto, but extending but five-eighths of 25 the distance around same. The ports 50 are located centrally of the ends 52 and 53 of the flanges 51, as shown in Fig. 3.

The spring 54 is arranged on the shaft 43 for the purpose of keeping the disk 30 valves 47 in proper engagement against the valve seats 30, 31, 32 and 33, respectively, and may be adjusted by means of the collar 55 and the set screw 56 on the shaft 43.

Rotation is imparted to the shaft 43 and 35 the disk valves 47, mounted thereon, by the driving gear 44 being geared to the crank shaft of the engine in any suitable manner, although any mechanical equivalent can be employed to rotate said shaft and 40 disk valves.

For the purpose of affording ready access to the valve devices and for assembling same, the valve casing 5 is made preferably with a removable portion 57, as illustrated 45 in Fig. 2, the other portion 58 of the valve casing 5, being formed integral with the engine casting. The two portions 57 and 58 of the valve casing 5, are securely held together and in position by means of the bolts 59.

50 As illustrated in Fig. 2, at 60 and 61, efficient arrangement is made to provide for water-cooling that part of the valve device which is most exposed to the firing.

Referring to Fig. 2, of the drawing, there 55 is shown a cross sectional view of the cylinder 1, provided with the annular chambered portion 62, for water cooling said cylinder, and with the usual spark plug 63. The piston 64 is operated in the usual manner from the crank shaft.

In operation, when the piston 64 has reached the end of its upward stroke and the products of combustion or exhaust are driven from the cylinder, the port 50 of the

disk valve 47 will be positioned directly 65 over the intermediate portion 42 of the valve seat 30 and the ports 34 and 38 of the said valve seat will be closed. When the piston 64 begins again to move downward, the port 50 of the disk valve 47, will register with the inlet port 34 of the valve seat 30, and a charge is drawn into the said cylinder through the port 65 in the lower section 18 in the valve chamber 6, and through the port 10 which communicates with the 75 cylinder 1. Being a four cycle type engine, when the piston 64 has reached the end of its downward stroke, the disk valve 47 will now have taken a one-quarter turn and the port 10 will be closed by the flange 51, on 80 the periphery of the disk valve 47. The inlet port 34 and the exhaust port 38 of the valve seat 30 will likewise be closed, and during the next two periods, that is during the upward or compression stroke of said 85 piston, and during the next downward or ignition stroke, will remain closed. At the last period, when the piston 64 begins to move upward, the port 50, of the disk valve 47, will register with the exhaust port 38, 90 in the valve seat 30, and the port 10 will likewise be opened, as the flange 51 will clear same during said period, and allow the exhaust to be forced from the cylinder 1 through the port 66 in the upper section 14 95 of the valve chamber 6.

From the foregoing description, taken in connection with the accompanying drawing, the operation, in practice, of the various cylinders with their respective valve 100 devices, will be readily understood without a more extended explanation, as all are identical in their construction, arrangement and operation, with the exception that the various disk valves are so adjusted upon the 105 shaft that said disk valves will act in timed relation with reference to the strokes of the pistons.

While describing the principle of operation of the invention together with the device which is now considered to be the best embodiment thereof, it is to be understood that various changes in the form, proportion and the minor details of construction may be resorted to without departing from 110 the principle or sacrificing any of the advantages of the invention as defined in the appended claim.

What I claim as new and desire to secure 120 by Letters Patent is:—

In valve mechanism in combination, a valve casing having the interior thereof divided by horizontal and vertical partitions into an upper gas chamber and a lower gas chamber, a vertical valve seat formed solid with the horizontal partition and arranged parallel to, but spaced from, one of the vertical partitions to form a valve chamber,

said seat having openings establishing communication between the valve chamber and upper and lower gas chambers, a cylinder communicating directly with the valve chamber and a rotatably mounted disk valve arranged in flat contact with the seat and having a port adapted to register with said openings, said disk valve being further provided with a peripheral flange having its 10 ends terminating short of said port in the

valve disk and extending at right angles thereto, said flange being of a width equal to the depth of said valve chamber.

In testimony whereof I affix my signature in the presence of two witnesses.

SAMUEL G. MILLIGAN.
